(57) **ABSTRACT**

A food slicing system includes a hub fixedly secured to a drive shaft and configured to rotate with the drive shaft. The hub has a central pilot projection coaxial with the drive shaft, and flat, blade contacting surface surrounding the pilot projection. A counterweight is eccentrically mounted to the hub and rotatable between a first position and an second position relative to the hub. Wherein when the counterweight is in a first position, the counterweight is in axial alignment with pilot projection, and permits the blade to be attached to or removed from the hub via movement of the blade in the axial direction. When the counterweight is in the second position, the counterweight is eccentric to the pilot projection and is offset from the axis of rotation, to provide a predetermined amount of weight offset from the axis of rotation to counterbalance the weight of the blade.

**BLADE ASSEMBLY AND COUNTERWEIGHT
MECHANISM FOR A HIGH-SPEED FOOD
SLICING APPARATUS, AND METHODS
ASSOCIATED WITH THE SAME**

**CROSS-REFERENCE TO RELATED
APPLICATION**

This application claims the priority of U.S. provisional application Ser. No. 63/271,459, filed on Oct. 25, 2021, the contents of which are incorporated herein in its entirety.

FIELD OF THE INVENTION

The present disclosure generally relates to an apparatus for slicing food products using a rotating blade, such as an involute blade, which is mounted on a hub and requires counterbalancing.

BACKGROUND

The present disclosure generally relates to an apparatus for slicing food products using a rotating blade, such as an involute blade. Blades of slicing machines are heavy, extremely sharp and dangerous to handle without proper safety practices. Slicing blades are mounted to and fixedly attached to a mounting assembly, such as a hub. Due to the geometry of involute blades, one side is heavier than the other. Accordingly, such blades must be balanced to permit high-speed rotation. In known equipment, a counterweight is added directly to the blade. In other equipment, the counterweight is added to the mounting assembly and requires removal and adjustment.

BRIEF DESCRIPTION OF THE DRAWINGS

The organization and manner of the structure and operation of the disclosed embodiments, together with further objects and advantages thereof, may best be understood by reference to the following description, taken in connection with the accompanying drawings, which are not necessarily drawn to scale, wherein like reference numerals identify like elements in which:

FIG. 1 is a perspective view of a food product slicing machine generally, according to one embodiment.

FIG. 2 is a perspective view of the food product slicing machine of FIG. 1, particularly showing the slicing blade and mount, according to one embodiment.

FIG. 3 is a perspective view of the food product slicing machine of FIG. 1, particularly showing the blade mount, according to one embodiment.

FIG. 4 is a perspective view of the food product slicing machine of FIG. 1, particularly showing a driven side of the blade mount, according to one embodiment.

FIG. 5 is a front view of the blade of the food product slicing machine of FIG. 1, according to one embodiment.

FIG. 6 is a side view of the blade and hub, according to one embodiment.

FIG. 7 is a perspective view of the hub with the counterweight in the first position, according to one embodiment.

FIG. 8 is a perspective view of the hub with the counterweight in the temporary position, according to one embodiment.

FIG. 9 is a perspective view of the hub and mounted blade, with the counterweight in the second position, according to one embodiment.

SUMMARY

A food slicing system for a high-speed food slicing machine includes an involute blade configured for rotation about a rotational axis, and having a central mounting aperture, a motor operatively coupled to a slicing assembly frame and configured to rotate a drive shaft, and a hub fixedly secured to a distal end of the drive shaft and configured to rotate with the drive shaft. The hub has a central pilot projection coaxial with the drive shaft, and a flat, blade contacting surface surrounding the pilot projection, where the pilot projection is configured to be received through the mounting aperture of the blade, to center the blade on the hub. A counterweight mounted to the hub is rotatable between a first position and a second position relative to the hub. When the counterweight is in the first position, the counterweight is in axial alignment with pilot projection, and permits the blade to be attached to or removed from the hub via movement of the blade in the axial direction and in a plane substantially parallel to a plane of the blade contacting surface. When the counterweight is in the second position, the counterweight is eccentric to the pilot projection and is offset from the axis of rotation, to provide a predetermined amount of weight offset from the axis of rotation to counterbalance the weight of the blade.

DETAILED DESCRIPTION

While the disclosure may be susceptible to embodiment in different forms, there is shown in the drawings, and herein will be described in detail, a specific embodiment with the understanding that the present disclosure is to be considered an exemplification of the principles of the disclosure, and is not intended to limit the disclosure to that as illustrated and described herein. Therefore, unless otherwise noted, features disclosed herein may be combined together to form additional combinations that were not otherwise shown for purposes of brevity. It will be further appreciated that in some embodiments, one or more elements illustrated by way of example in a drawing(s) may be eliminated and/or substituted with alternative elements within the scope of the disclosure.

Referring now to FIGS. 1-6, a food product slicing apparatus 20 is used to slice food products into slices. The food products may include a wide variety of edible materials including, but not limited to meat, such as pork bellies, beef, chicken, fish, etc., and cheese.

The food product slicing apparatus 20 includes a main frame 22, a load assembly 24 mounted on the main frame 22, a feed assembly 26 mounted on the main frame 22 downstream of the load assembly 24, a slicing assembly 28 mounted on the main frame 22 downstream of the feed assembly 26, and an output assembly 30 mounted on the main frame 22 downstream of the slicing assembly 28. The food product slicing apparatus 20 further includes a control system 32 configured to control operation of the components of the food product slicing apparatus 20.

The main frame 22 supports the load assembly 24, the feed assembly 26, the slicing assembly 28, and the output assembly 30 on a ground surface, and includes various mechanisms and power systems for powering the food product slicing apparatus 20. The load assembly 24 and the feed assembly 26 are configured to support and handle the food products and to move the food products to the slicing assembly 28. The slicing assembly 28 is configured to slice the food products into individual slices. The sliced food product is supported on the output assembly 30, which may

be a conveyor, in stacks or in shingles and is moved away from the slicing assembly 28. The control system 32 includes all the necessary hardware and software to perform all of the operations and functions of the food product slicing apparatus 20. The control system 32 may be mounted on the main frame 22 or may be remote from the main frame 22.

The slicing assembly 28 includes a shear bar 340, a food product gripping assembly (not shown) on the shear bar 340 (FIG. 3) that cooperates with the feed roller 172 (FIG. 3) on the feed assembly 26, a slicing blade 344 for cutting the food products into slices, and a blade retract and driving system 346 (FIG. 4) for mounting the slicing blade 344 on the main frame 22 and rotating the slicing blade 344. The shear bar 340 and the food product gripping assembly 342 are downstream of the drive assembly 106. The slicing blade 344 is downstream of the shear bar 340. The feed roller 172 and the food product gripping assembly 342 grip the food products as the food products are being sliced by the slicing blade 344.

Referring now to FIGS. 2-9, a blade counterweight mechanism 2410 is described. The blade 344, which is preferably an involute blade, may be mounted on a hub 3110. The hub 3110, in turn, is driven by a motor 404 operatively coupled to the slicing assembly frame 4010. The motor 404 may directly drive a shaft 4020 of the hub 3110, or may indirectly drive the shaft 4020 of the hub 3110 by a belt 408 and/or pulley 396 arrangement, according to a preferred embodiment.

The hub 3110 is fixedly secured to a distal end of the drive shaft 4020 and configured to rotate with the drive shaft 4020. The hub 3110 includes a central pilot projection 3120, which is coaxial with the drive shaft 4020. The pilot projection 3120 may be a separate disk-like component fastened to the hub 3110 with a plurality of bolts 5010, or may be integrally formed with the hub 3110. The pilot projection 3120 may be elevated above the surface 3030 of the hub 3110, which hub surface 3030 forms a flat, blade contacting surface 3030, that surrounds the pilot projection 3120.

The pilot projection 3120 is configured to be received through the mounting aperture 2020 of the blade 344 so as to center the blade 344 on the hub 3110. The pilot projection 3120 projects above a surface of the hub 3110 by a distance less than or equal to a thickness of the blade 344 as measured at the mounting aperture 2020 of the blade 344.

As best shown in FIG. 6, the blade counterweight mechanism 2410 further includes a rotatable weight or counterweight 414 eccentrically mounted to the pilot projection 3120 by a bolt or pivot pin 416 and which extends through a portion of the rotatable counterweight 414. An inner race of a bearing 418 is affixed to the pivot pin 416 and an outer race of the bearing 418 is affixed to the rotatable weight 414. The rotatable counterweight 414 can rotate relative to the hub 3110 about the pivot pin 416 via the bearing 418.

The rotatable counterweight 414 may be rotated between a first position 7010 and a second position 2410. When the counterweight 414 is in the first position 7010, the counterweight 414 is in axial alignment with pilot projection 3120. In this position, the blade 344 may be attached to or removed from the hub 3110 via movement of the blade 344 in the axial direction and in a plane parallel to a plane of the blade contacting surface 3030. Essentially, the blade 344 may be removed from the hub 3110 or a new blade may be attached to the hub 3110 via axial movement of the blade 344, while maintaining the blade in the same plane as the surface of the hub 3110. This may be performed for blade replacement or servicing.

While the counterweight 414 is in the first position 7010, in operation, a new blade is then affixed to the hub 3110. Once the mounting aperture 2020 of the new blade has been positioned over the pilot projection 3120 and the blade body 5 is in contact with the blade contacting surface 3030 of the hub 3110, the counterweight 414 may be permitted to temporarily hang downwardly 8020 and freely pivot about the pivot pin 416 under the force of gravity, as shown in FIG. 8, with blade omitted for clarity. This temporary position 10 8020 of the counterweight 414 provides a mechanism to temporarily hold the blade 344 in place, in a non-operational manner. The blade 344 may then be fixedly mounted to the hub 3110 using a plurality of bolts 5130 spaced evenly about a circumference of the mounting aperture 2020 of the blade 15 344, and where the plurality of bolts 5130 are displaced radially outwardly from a perimeter of the mounting aperture 2020.

Once the blade 344 has been securely bolted to the hub 3110, as shown in FIG. 9, the rotatable counterweight 414 20 may be rotated from the first position 7010 to the second position 2410 by rotating the counterweight 414 in the clockwise direction about the pivot pin 416 until an outer wall 9030 of the counterweight 414 contacts a stop pin 7012, which projects from the blade contacting surface 3030.

When the counterweight 414 is in the second position 2410 stopped in place by the stop pin 7012, a locking bolt 420 is inserted through a through bore 6020 in the counterweight 414, and the end of the locking bolt 420 is received within a corresponding threaded aperture in the pilot projection 3120. In this position, the locking bolt 420 is tightened so as to "sandwich" the blade 344 between the blade contacting surface 3030 of the hub 3110 and an inner surface of the counterweight 414. The locking bolt 420 may be completely removable, or may be partially held in place by a grommet to avoid dropping or losing the locking bolt.

It is important to note that whether in the first position 7010 or in the second position 2410, the counterweight 414 is not detachable from the hub 3110, and always remains attached to the hub 3110, although rotatable relative thereto. 40 Thus, removal and attachment of the blade 344 may be performed without the need to remove the counterweight 414. Accordingly, the counterweight 414 remains rotatably attached to the hub 3110 while the blade 344 is removed from the hub 3110, and remains rotatably attached to the hub 3110 while the blade 344 is secured to the hub 3110. This increases safety and convenience, while reducing the time required to change or service the blade 344.

The angular position of the counterweight 414 relative to the hub 3110, as dictated by placement of the locking bolt 50 420 determines the balancing effect of the counterweight 414 as the hub 3110 and blade 344 rotate. Due to the angular offset of the counterweight 414 relative to the axis of rotation, the center of mass of the counterweight 414 counterbalances the weight of the involute blade 344, as the weight of the involute blade is greater at one end than the other, due to its spiral shape.

In another embodiment, the hub 3110 may include cut-out areas 7040 where material is removed or has been omitted to provide further counterbalance and torque control of the hub 60 3110. As shown in the figures, one or more cutout portions 7040 may be formed in the body of the hub 3110 about a semicircular portion of the hub 3110, which is preferably located at a side of the hub 3110 away located from the counterweight. In this embodiment, because a predetermined of mass is removed from one portion of the hub 3110 which is countered by the counterbalance 414, the torque about the drive shaft is equalized to prevent wobble.

While a particular embodiment is illustrated in and described with respect to the drawings, it is envisioned that those skilled in the art may devise various modifications without departing from the spirit and scope of the appended claims. It will therefore be appreciated that the scope of the disclosure and the appended claims is not limited to the specific embodiment illustrated in and discussed with respect to the drawings and that modifications and other embodiments are intended to be included within the scope of the disclosure and appended drawings. Moreover, although the foregoing descriptions and the associated drawings describe example embodiments in the context of certain example combinations of elements and/or functions, it should be appreciated that different combinations of elements and/or functions may be provided by alternative embodiments without departing from the scope of the disclosure and the appended claims.

The invention claimed is:

1. A food slicing system for a high-speed food slicing machine, comprising:

an involute blade configured for rotation about a rotational axis, and having a central mounting aperture; a motor operatively coupled to a slicing assembly frame and configured to rotate a drive shaft;

a hub fixedly secured to a distal end of the drive shaft and configured to rotate with the drive shaft; the hub having a central pilot projection coaxial with the drive shaft, and having a flat, blade contacting surface surrounding the pilot projection, wherein the pilot projection is configured to be received through the mounting aperture of the blade, to center the blade on the hub;

a counterweight mounted to the hub and rotatable between a first position and a second position relative to the hub;

wherein when the counterweight is in the first position, the counterweight is in axial alignment with pilot projection, and permits the blade to be attached to or removed from the hub via movement of the blade in an axial direction and in a plane substantially parallel to a plane of the blade contacting surface; and

wherein when the counterweight is in the second position, the counterweight is eccentric to the pilot projection and is offset from the rotational axis, to provide a predetermined amount of weight offset from the rotational axis to counterbalance the weight of the blade.

2. The food slicing system according to claim 1, wherein the pilot projection is a separate disk-like component and is fastened to a portion of the hub.

3. The food slicing system according to claim 1, wherein the pilot projection is integrally formed with the hub.

4. The food slicing system according to claim 1, wherein the pilot projection projects above a surface of the hub by a distance less than or equal to a thickness of the blade at the mounting aperture of the blade.

5. The food slicing system according to claim 1, wherein the hub includes cut-out areas where material is removed to provide further counterbalance and torque control of the hub.

6. The food slicing system according to claim 1, wherein the counterweight remains rotatably attached to the hub in the first position while the blade is removed from the hub, and remains rotatably attached to the hub in the second position while the blade is secured to the hub.

7. The food slicing system according to claim 1, wherein the counterweight remains rotatably attached to the hub at all times during removal and installation of the blade on the hub.

8. The food slicing system according to claim 1, wherein the blade is fastened to the hub by a plurality of bolts spaced evenly about a circumference of the mounting aperture of the blade, and wherein the plurality of bolts are displaced radially outwardly from a perimeter of the mounting aperture of the blade.

9. The food slicing system according to claim 1, wherein when the counterweight is in the second position and the blade is disposed between the blade contacting surface of the hub and an inner surface of the counterweight, a counterweight fixing bolt urges the counterweight toward the hub to fixedly secure the blade between the hub and the counterweight.

10. A food slicing system for a high-speed food slicing machine having an involute blade configured for rotation about a rotational axis and a motor configured to drive a drive shaft, the food slicing system comprising:

a hub fixedly secured to a distal end of the drive shaft and configured to rotate with the drive shaft, the hub having a central pilot projection coaxial with the drive shaft, and having a blade contacting surface surrounding the pilot projection, wherein the pilot projection is configured to be received through a mounting aperture of the blade, to center the blade on the hub;

a counterweight mounted to the hub and rotatable between a first position and a second position relative to the hub;

wherein when the counterweight is in the first position, the counterweight is in axial alignment with pilot projection, and permits the blade to be attached to or removed from the hub via movement of the blade in an axial direction and in a plane parallel to a plane of the blade contacting surface; and

wherein when the counterweight is in the second position, the counterweight is eccentric to the pilot projection and is offset from the rotational axis, to provide a predetermined amount of weight offset from the rotational axis to counterbalance the weight of the blade.

11. The food slicing system according to claim 10, wherein the pilot projection is a separate disk-like component and is fastened to a surface portion of the hub or is integrally formed with the hub.

12. The food slicing system according to claim 10, wherein the pilot projection projects above a surface of the hub by a distance less than or equal to a thickness of the blade at the mounting aperture of the blade.

13. The food slicing system according to claim 10, wherein the hub includes cut-out areas where material is removed to provide further counterbalance and torque control of the hub.

14. The food slicing system according to claim 10, wherein the counterweight remains rotatably attached to the hub while the blade is removed from the hub, and remains rotatably attached to the hub while the blade is secured to the hub.

15. The food slicing system according to claim 10, wherein the counterweight remains rotatably attached to the hub at all times during removal and installation of the blade on the hub.

16. The food slicing system according to claim 10, wherein the blade is fastened to the hub by a plurality of bolts spaced evenly about a circumference of the mounting

aperture of the blade, and wherein the plurality of bolts are displaced radially outwardly from a perimeter of the mounting aperture of the blade.

17. The food slicing system according to claim 10, wherein when the counterweight is in the second position and the blade is disposed between the blade contacting surface of the hub and an inner surface of the counterweight, a counterweight fixing bolt urges the counterweight toward the hub to fixedly secure the blade between the hub and the counterweight.

18. A method of balancing an involute blade in a food slicing system for a high-speed food slicing machine, the involute blade configured for rotation about a rotational axis, the high-speed food slicing machine having a motor configured to drive a drive shaft, the method comprising:

fixedly securing a hub to a distal end of the drive shaft;

providing a central pilot projection on the hub coaxial with the drive shaft, and providing a blade contacting surface surrounding the pilot projection;

pivotally mounting a counterweight to the hub to permit the hub to rotate about a pivot point, between a first position and an second position relative to the hub;

removing the blade from the hub when the counterweight is in the first position, via movement of the blade in an axial direction and in a plane parallel to a plane of the blade contacting surface, wherein the counterweight is in axial alignment with pilot projection in the first position;

attaching a new blade to the hub when the counterweight is in the first position so that the pilot projection is received within a central mounting aperture of the new blade;

rotating the counterweight from the first position to the second position so that the counterweight is eccentric to the pilot projection and is offset from the rotational axis, wherein the blade is disposed between the blade contacting surface of the hub and an inner surface of the counterweight; and

tightening a fixing bolt to fixedly secure the counterweight to the hub and to secure the blade between the hub and the counterweight.
